UNITED STATES PATENT OFFICE.

WILLIAM E. BARTON, OF EAST HAMPTON, CONNECTICUT.

DESIGN FOR A BELL.

SPECIFICATION forming part of Design No. 14,263, dated September 11, 1883.

Application filed July 30, 1883. Term of patent 14 years.

To all whom it may concern:

Be it known that I, W.M. E. BARTON, of East Hampton, in the county of Middlesex and State of Connecticut, have invented a new Design 5 for Bells; and I do hereby declare the following, when taken in connection with accompanying drawing and the letters of reference marked thereon, to be a full, clear, and exact description of the same, and which said drawing constitutes part of this specification, and represents a side view.

This invention relates to a design for that class of bells which are open-mouthed and hung at the top to a handle or other attachment by which the ringing is produced; and the design consists in the configuration of the exterior of the bell, as shown in the accompanying illustration, and hereinafter described.

The bell represents two sections, the lower 20 section, A, being substantially the shape of the usual gong-bell. This is surmounted by the second section, B, of considerably smaller diameter than the larger diameter of the lower

portion, and so as to give the appearance of a line or angle, *a*, on the surface of the bell between the two sections. The upper section, B, is gradually contracted to the top, where the handle may be applied. The upper section may be somewhat changed in its outline without departing from the design, the essential feature of the design being the lower or gong-shaped section with an upper section springing from it, and so as to produce the appearance of a defined line between the two. 25 30

I claim—

The herein-described design for a bell, consisting of the lower gong-shaped section A, the upper section, B, springing from the top of the lower section, and of less diameter, and so as to produce the appearance of an angle 35 40 between the two sections, as shown in the accompanying illustration.

WILLIAM E. BARTON.
